UNITED STATES PATENT OFFICE

MAURICE SAMBURG AND JULIUS C. HOCHMAN, OF NEW YORK, N. Y.

MULTIPLE TOTALIZER ATTACHMENT FOR TYPEWRITERS

Application filed January 24, 1920, Serial No. 353,830. Renewed May 12, 1928.

This invention has as one of its objects to provide a mechanism, applicable to a typewriter, in such manner as to actuate the numeral keys thereof and by such means operate one or more of a plurality of totalizers, arranged to show various lists used in accounting, billing and bookkeeping, as the accretion of items, charges, payments, discounts, balances, etc., etc., in detail as may be desired, the mechanism being an improvement, by reason of its increased scope, capacity and general utility, over that disclosed in the patent granted to us November 30, 1926, bearing No. 1,609,205, in which the structural details are fully set forth.

A further object is to provide such attachments in forms which may be readily attached to any ordinary typewriting machine without damage or change to the same, and which in no manner interferes or conflicts with its usual, customary functions in writing either alphabetical characters or numerals, the type and keys of the machine being used independently of, or conjunctively with, the attachment as desired.

Another object is to provide a device capable of performing all of the several functions of competitive devices in a satisfactory manner, the device being relatively inexpensive in construction and capable of long and continued service.

These and corresponding objects are attained by the novel construction and combination of parts, hereinafter described and shown in the accompanying drawings, forming a material part of this disclosure, and in which:—

Figure 1 is a horizontal longitudinal sectional view of a mechanism made in accordance with the invention, the section being immediately below the cover plate.

Figure 2 is a partial vertical sectional and front elevational view of the same.

Figure 3 is a side elevational view showing the apparatus as applied to a typewriting machine.

Figure 4 is an enlarged transverse sectional view taken on line 4—4 of Fig. 2.

Figure 5 is a similar sectional view taken on line 5—5 of Fig. 2.

Figure 6 is another sectional view taken on line 6—6 of Fig. 2.

Figure 7 is another like sectional view taken on line 7—7 of Fig. 2.

Figure 8 is a fragmental longitudinal sectional view taken through certain of the totalizers.

Figure 9 is an enlarged transverse sectional view taken approximately on line 9—9 of Fig. 8.

Figure 10 is a similar sectional view taken on line 10—10 of Fig. 8.

Figure 11 is a fragmentary partial side and sectional view showing the mutilated totalizer carriage actuating ratchet wheel.

Figure 12 is a fragmentary sectional view similar to Fig. 9, but showing a modification thereof.

Referring to the drawings in detail, particularly Fig. 3, the numeral 20 designates in general a typewriting machine having all of the usual parts, including upper and lower case alphabetical, and numeral keys 21, with their levers 22 operatively engaged to perform their customary functions.

The mechanism, in the form of an attachment, is secured to the upper front part of the machine in such position as to avoid obscuring any essential part, or interfering with the use of the key board, or mutilating or disfiguring the machine in any manner.

A plate base 25 is secured by screws in front of the type basket, in a vertical plane, its parallel upper and lower edges being horizontal and level. Formed in the front of the plate 25 are ten vertical guide grooves 26, spaced to agree with the typewriter numeral key levers 22, including the lower case letter "7", used also for the numeral "1".

Slidably in the grooves are bars 28, held therein by a cross strip 29, their lower ends resting lightly and unconfinedly upon the key levers, and having outwardly extending finger pads 30 displaying numerals from 0 to 9, inclusive, these pads being arranged for convenience of access.

The upper portions of the bars 28 extend into a casing, generally designated by the numeral 33, and terminate in angles 31, arranged in a uniform horizontal row therein.

The casing 33 is secured to the front of the plate 25 and extends across the entire front of the machine as indicated.

Fixed in the casing are support plates 34 and 34', near the right and left hand ends respectively, and journalled near their upper front curved corners is a shaft 35, extending through the right side of the casing and provided with a knob 36 by which it may be turned.

Another shaft 38 is rotatably mounted in the plates nearly at their centers, while also extending across near their bottoms is a fixed rod 39.

15 Fixed to the shaft 38, adjacent the inner surface of the plates 34 and 34', are spur gears 40 engaging with racks 41, formed on the front edges of extensions 42, bent forward at right angles from a plate 43, limited 20 to slidable movements up or down adjacent to the support plate 25, by reason of movement imparted by the angular ends 31 of the numeral key bars, the plate, which extends lengthwise within the casing, being 25 returned to a normal raised position by springs 47 near its ends, and caused to move in a bodily uniform manner by the equalizing gears and racks 40 and 41. The plate 43 may also be directly actuated by a back 30 space or resetting key 44 whenever desired, as will be further explained.

Adjacent the plate 43 is another longitudinal plate 45 having a plurality of steps 46 on its upper edge, corresponding to the 35 numerical value of the key depressed, and carrying at its extreme ends pairs of opposed inner and outer racks 48 and 50, either pair being independently engageable with spur pinions 51 fixed on the ends of a tubular 40 sleeve 52, slidably mounted on the shaft 38 and shiftable thereon by an extending lever 53.

As the angular ends 31 also extend over the plate 45 motion is communicated to it by 45 depressing the numeral key bars 28 and rotary motion conveyed to the sleeve 52 in either direction, according to the position of the shift lever 53, while at the same time the pinions and racks act as equalizers for the 50 plate 45.

Circumjacent to the sleeve 52, on the shaft 38, is another tubular sleeve 55 of lesser length and having slidably attached at its right hand end an annularly recessed collar 56, engaged by the forks 57, pivoted on the pin 58, the forks being actuated by an operating lever 59 extending through the casing, and thus transmitting motion to the shiftable actuator gear 64.

60 Also fixed on the sleeve 55 are spur gears 61, 62, 63, which with the gear 64 are adapted to actuate the four totalizers shown, the wheels of which are rotated in proportion to the depression of the stepped plate 45, as 65 further on described.

In the lower edge of the plate 45 are a series of recesses 66, differing in extent of length and arranged in register with the bars 28, adapted to limit the downward movement of the plate and preventing over travel due to inertia.

70 These slots receive the upper ends of detent levers 67, the lower ends of the levers engaging in slots 68, in the bars 28 and are normally held out of contact by springs 69. The detent levers are spaced apart by the spacing sleeves 70, which are fixed on the rod 39, and are operated by the depression of the key bars in an obvious manner.

75 The totalizers, of which four are preferably used, identified by letters A, B, C and D, are essentially alike in their construction, except the fourth totalizer D, which preferably has more totalizer wheels, and are mounted on the shaft 35, each consists of a plurality of discs or centers 100 having integral lateral extensions 101 on one side, 80 upon which are formed ten peripheral teeth 102.

These teeth are engageable by a single tooth 103, formed with a pawl 104 pivoted by a pin 105 fixed in the side of the adjacent wheel, and normally held out of engagement by a curved flat spring 106, held by the pin 107 to the adjacent wheel at a point opposite the pin 105.

85 The tooth 103 is caused to engage the spaces between the teeth 102, one at each revolution, of the adjacent element and perform a tens-carrying operation by reason of a lug 108, formed with the pawl 104, and contactable, when traveling in either direction, with a cam-like projection 110 formed with a comb-like plate 111 secured to the inner surface of the totalizer frame 112.

90 Secured over the bodies or centers 100 are tubular casings 115, and integrally formed with the centers 100 at one end thereupon, are ten teeth 116, engageable with the actuating gears 61, 62, 63 and 64, as the totalizers are moved lengthwise of the shaft.

95 In order to provide means for resetting three sets of the totalizer wheels at zero, the shaft is grooved longitudinally a corresponding length, forming a key-way 118, 100 into which may enter a ball or sphere 119, pressed by the spring 120 contained in the opening 121 in the bodies 100, the springs being covered by the casings 115, in such manner as to engage the slot 118, with sufficient force as to turn the wheels in one direction when the shaft 35 is rotated by twirling the knob 36.

105 This motion of the shaft however does not affect the totalizer at the extreme right, 115 which is reset by subtracting the amount shown, while recording the total upon the typed sheet.

120 The totalizers are moved lengthwise on the shaft by a rack 125, fixed on the back of 130

the frame 112, the same being enmeshed with a gear 126 fixed on the end of a transverse spindle 127 journaled partially in a bracket 128 and the back plate 25.

5 Also fixed on the spindle 127 is a mutilated ratchet wheel 130, having an intermission of its teeth, as at 131, (see Fig. 11) the ratchet wheel being arranged closely adjacent the back space plate 43, which is provided with a 10 slot 132 permitting the plate to move with reference to the spindle.

Carried on the plate 43 is a spring actuated pawl 133, pivoted on the pin 134, the free end of the pawl being held in operative 15 position by a fixed pin 135 so as to engage the teeth when the spindle has been partially turned, but riding free along its periphery at the blank space 131, thus permitting the plate 43 to be moved at certain times without 20 conveying motion to the spindle and thus to the totalizer frame, as when the machine is in an inoperative condition.

A drum 140 is journaled within the casting 33, near its right hand end, on a spindle 25 141, to which is attached the inner end of a flat spirally coiled spring 142, by which the drum is rotated, and attached to wind upon the exterior of the drum is a flexible tape 143, engaging the totalizer frame in such 30 manner as to draw the totalizers collectively to the right.

A plurality of separate lever stops, 145, 146, 147, 148, 149 and 150 are pivoted on a pin carried in a loop bracket 152, pivoted at 35 its lower angular end by a screw 153 to the plate 25, these levers being upwardly inclined at their free ends and arranged so that the longest lever is depressed only after the selected stop has been brought into operative 40 position. Each lever stop is preferably arranged with transverse lugs (not shown) extending across all companion levers of greater length so that upon depressing any lever stop by the actuation of the corresponding 45 tabulating key, all of the stops of greater length would be depressed therewith out of the path of the totalizer carriage stop. The specific details of the construction are fully shown and claimed in the patent granted to 50 us on November 30, 1926, bearing No. 1,609,205.

Formed with the outer stop lever 150 is a raised projection 151 limiting the ultimate travel of the totalizers to the right, in its 55 last or highest decimal position. The angular position of the carrying bracket 152 is controlled by a hand lever 154 so that the contacting ends of the stops may be collectively moved to bring one or more of the 60 totalizers into operative engagement with the actuator gears 61, 62 and 63, which vary in width.

The lever 154 is shown in Fig. 2 in its extreme position to the left, in which all of 65 the totalizers are disengaged from the actu-

ator gears. By shifting the lever 154 to the first of the dot and dash positions indicated on Fig. 2, the shift bracket is moved to bring totalizer C into mesh with gear 63, while totalizers B and A remain out of mesh with gears 62 and 61. Shifting lever 154 to the next dot and dash position effects mesh of the totalizer B with gear 62. When lever 154 is moved to the extreme position toward the right, as indicated by the extreme dot and dash line, gear 61 is also meshed with the corresponding totalizer A, so that all three of the totalizers, A, B and C, corresponding to gears 63, 62 and 61 are brought into mesh. Thus, depending upon the position of the lever 154, all of the totalizers A, B and C are disengaged, totalizer C alone is engaged or the two totalizers C and B are engaged or all three totalizers A, B and C are engaged. The totalizer D furthest to the right is engaged by the actuator gear 64 moved independently by the lever 59, this totalizer alone being reset by direct subtraction.

Operatively engaging the stop levers are individual keys 155, 156, 157, 158, 159 and 160 bearing designations representing decimal values, as units, tens, hundreds, etc., by which the numeral wheels are located in decimal relation, it being understood that the distance between the ends of adjacent stops is equal to the distance between adjacent wheels in the totalizers. Thus all of the totalizers are drawn by the spring 142 against the stops, which are held normally in a raised position by a comb spring 162 and are individually depressible by the decimal keys as desired.

In operation, if it be desired to actuate all of the totalizers and the same having been cleared to present ciphers, the lever 154 is moved fully to the right and the lever 59 also moved to the right.

Let it be assumed that the number 728 is to be added to 4362. The first operation is to set up the number 4362 which is accomplished by depressing the thousands key 157, which permits the totalizer to move to the right, under the pull of the spring, until contact is made with the stop 148, moving the totalizer four places.

The key bar 28, carrying the numeral "4" is pressed, causing the typewriter to print, while coincidentally the plates 43 and 45 are moved down, by engagement with the hook ends 31 of the bars 28, in parallel lines, due to the equalizing devices at their ends, the racks 48 or 50 rotating the pinions 51, transmitting rotary motion to the actuator gears and by them to the fourth wheels (counting from the right of the totalizer), causing them to display the numeral 4.

Upon being released the plates are returned to a normal raised position by the springs 47, the pawl 133, carried on the plate 43, engaging with the teeth of the ratchet wheel 130,

turning the gear 126, which being engaged with the totalizer frame rack 125, moves the totalizers against the pull of the spring 142, one space so that the frame abuts against the 5 next stop 146 automatically.

The key bar, representing the numeral "3," is then depressed, causing a corresponding, simultaneous printing and movement of the 10 next adjacent numeral wheels of the totalizer at the right, setting up the figure "3," and obviously the remaining figures "6" and "2" are similarly printed and disclosed coincidently on the totalizers.

The totalizers now being disposed so as to 15 display units, the hundreds key 156 is pressed, allowing the totalizer frame to be drawn by the spring into contact with the stop 147, whereupon the key bar carrying the numeral 7 is actuated, the paper in the typewriter having previously been adjusted to present a proper line space, and also to cause correct decimal vertical registration, the figure 7 is printed and added to the number "3" on the 20 totalizer wheels, causing them to register zero 25 and, due to their interengaging construction, carry "1" to the wheels adjacent on the left, disclosing 5062 as the partial sum.

Depressing the key bar 2 prints and adds "2" to "6," showing 5082 and finally depressing 30 the key bar "8" adds "8" to "2," which, by carrying means employed, discloses the full sum of 5090, which, after drawing a line if desired on the paper in the typewriting machine, may be transferred by the normal use 35 of the typewriter keys, together with any signs, or symbols as may be desired, as for instance the dollar mark, etc.

Thus the correct sum appears through 40 openings in the casing and has also been written by the keys of the typewriter.

In the modified form of totalizer shown in Fig. 12 a spring 106' acts to press the V-shaped tooth of the pawl 104' into engagement with the teeth 102 of the ratchet wheel, 45 the tooth of the pawl touching at its extreme point and along one of its angular edges. The hump 108' is held down by the projection 110 when the gear to which the pawl is attached is driving, but when the ratchet wheel 50 is driving, the pawl is raised, clearing the projection 110 and allowing the ratchet to click past the pawl without conveying motion to it.

Three of the totalizers may now be cleared 55 by the knob 36, and if desired, the sum 5090 may be kept in the totalizer at the extreme right, this totalizer thus acting as a continuous accumulator of individual totals. Such a continuous accumulator is used for recording 60 daily totals, and is reset at the end of the day by subtraction.

The disclosure is however to be regarded as descriptive only and not as restrictive or limitative of the invention, of which obviously 65 an embodiment may be constructed includ-

ing many minor modifications without departing from the general scope herein indicated and mentioned in the appended claims.

We claim:

1. A self-contained computing mechanism 70 comprising a casing adapted to be engaged with a typewriter, a carriage in said casing, a plurality of totalizers in said carriage, a single-tractive means for said carriage and all of said totalizers, driving means for all 75 said totalizers, a single set of bodily shiftable decimal limit stops for simultaneously setting all said totalizers, and means for returning said totalizers to their initial position.

2. A combined typewriter and computing 80 mechanism comprising a typewriting mechanism, a self-contained computing unit secured to said typewriting mechanism, means for operating the number keys of said typewriting mechanism independently of the 85 computing mechanism, means for operating the computing mechanism concurrently with the numeral type bars of the typewriting mechanism, said computing mechanism having a plurality of totalizers, means for clearing certain of said totalizers collectively, and means for clearing one of said totalizers by subtraction and simultaneously printing the 90 total registered by the typewriting mechanism.

3. A mechanism having a plurality of totalizers, a keyboard connected for simultaneous actuation of all of said totalizers, said mechanism adapted to be mounted upon a typewriting machine of standard construction with the numeral key levers of the typewriter in the path of movement of the corresponding keys of the computing mechanism, said mechanism including means for clearing a plurality of totalizers collectively, 100 and means whereby one of said totalizers may be cleared by subtraction.

4. A computing mechanism comprising a casing engaged with a typewriter, a plurality of totalizers movable therein, selective 110 driving means therefor, a stepped plate, means carried by said plate for actuating said driving means and said totalizers, and means for operating said plate together with the numeral keys of said typewriter.

5. A computing mechanism engaged with a typewriter over the keys thereof, a plurality of totalizers in said mechanism, means for alternatively connecting one or more of said totalizers for operating independently of the other totalizers, and means for concurrently operating said totalizers and the numeral keys of the typewriter, and a single means cooperative with said totalizers for decimal- 120 ly spacing the same.

6. A computing mechanism comprising a casing engaged with a typewriter, totalizers movable therein, totalizer selective driving means therefor, a longitudinally movable stepped plate, means carried thereby for 125 130

- operating said driving means and said totalizers, means for operating said plate together with the numeral keys of the typewriter, and means for shifting the direction of rotation of the wheels in said totalizers. 5
7. A computing mechanism comprising a casing engaged with a typewriter, totalizers movable therein, a continuous accumulator coaxial therewith, a rotatable shaft mounted longitudinally in said casing, a driving gear for each totalizer and for said accumulator mounted on said shaft, and means for shifting said totalizers and said accumulator to engage their numeral wheels with said driving gears. 10
8. A computing mechanism comprising a casing engaged with a typewriter, totalizers movable therein, a rotatable shaft mounted longitudinally in said casing, driving gears for each totalizer, said gears being of different thickness, and fixed on said shaft, means for engaging one or more of said totalizers with said gears, and means for actuating said gears coincident with the typewriter numeral keys. 15
9. A computing mechanism, in engagement with a typewriter comprising, a movable carriage, a plurality of totalizers in said carriage, selective driving means engageable with one or more of said totalizers, and keys for actuating the engaged totalizers, said keys resting unconfinedly but operatively on the numeral keys of the typewriter. 20
10. A computing mechanism combined with a typewriter including a carriage and a plurality of totalizers, driving means therefore, means for selecting the totalizers to be driven, means for decimal setting said totalizers, cooperative with said selecting means, a single tractive means for said carriage, and means for returning said carriage to its initial position. 25
11. A computing mechanism for a typewriter operably engaged therewith entirely independent of its functions including a plurality of totalizers, a single tractive means for all of said totalizers, a single series of shifting decimal stops for all said totalizers, and means for shifting said stops. 30
12. A computing mechanism for a typewriter operably engaged therewith entirely independent of its functions including a plurality of totalizers, a single tractive means for all of said totalizers, a single series of shifting steps for said totalizers, gears engageable with the numeral wheels of said totalizers, and means for shifting said stops so as to cause engagement of one or more of said totalizers with said gears. 35
13. A computing mechanism having a carriage and a plurality of totalizers movable therein, tractive means for said carriage, and a series of stops which may be singly and collectively operated for limiting the advancement of said carriage, said stops being bodily movable to alter the stationary position of said carriage and of said totalizers. 40
14. A computing mechanism inclusive of a casing engaged with a typewriter, a carriage and a plurality of totalizers movable in said casing, tractive means for said carriage, a series of stops for said carriage, and means for actuating said stops singly or collectively for limiting the advancement of said carriage, said stops being bodily movable to alter the stationary position of said carriage and of said totalizers. 45
15. A computing mechanism for a typewriter, operably engaged therewith independent of its function, a slideable carriage containing totalizers operatively engaged in said mechanism, lever stops inclined upwardly at their operative ends against which said carriage abuts, and means for shifting said stops into different positions. 50
16. A computing mechanism for a typewriter operably engaged therewith independent of its functions, a carriage slidably mounted therein having totalizers operatively engaged in said mechanism, lever stops inclined upwardly at their free ends against which said carriage abuts, means for actuating said stops independently, the first of said stops holding the carriage and its totalizers until the stops beyond the selected one are displaced and means for shifting said stops bodily. 55
17. A computing machine including a totalizer, means for moving said totalizer in one direction, and means for returning said totalizer, said means providing for a non-operative home position. 60
18. A computing mechanism for a typewriter operably engaged therewith entirely independent of its functions, a plurality of totalizers movable in said mechanism, tractive means for all of said totalizers, and a series of shifting stops for operatively selecting a predetermined totalizer alone or with one or more of the other totalizers. 65
19. A computing mechanism operably engaged with a typewriter having a letter space escapement, said computing mechanism comprising a casing, a carriage in said casing, totalizers movable therein, an independent escapement for said carriage, a rotatable shaft mounted longitudinally in said casing, a driving gear for each totalizer on said shaft, and means for engaging one or more of said totalizers with said driving gears. 70
20. A computing mechanism combined with a typewriter having letter and numeral keys, a movable typewriter carriage and means actuated by said keys for moving said carriage at spaced intervals to the left, a carriage in said computing mechanism, a plurality of totalizers therein having individual drive gears, computing keys for actuating the wheels of said totalizers, and means controlled by said keys for returning said carriage to the right. 75

- mentioned carriage to the left in a step by step movement and coincidentally operating the numeral keys of the typewriter.
21. A computing mechanism engaged with a typewriter at the upper front part thereof, a plurality of totalizers movable longitudinally in said mechanism, tractive means for said totalizers, decimal spacing stops, means for actuating said stops whereby said totalizers are initially positioned, gears for actuating the wheels of said totalizers, and numeral keys for coincidentally actuating said gears, the numeral keys of the typewriter, and a carriage shifting means, whereby the totalizers are advanced upon rotation of their numeral wheels. 75
22. A computing mechanism in engagement with a typewriter, comprising a movable carriage, a plurality of totalizers in said carriage, a driving gear for each of said totalizers, shiftable means engaging one or more of said totalizers to its driving gear, and keys for actuating the driving gears and the engaged totalizers, said keys being positioned non-interferingly but operatively above the numeral keys of the typewriter. 80
23. A computing mechanism including a plurality of totalizers, means for driving each of said totalizers, shiftable stop means for engaging said totalizers with said driving means, and additional means for disengaging the driving means for one of said totalizers in any position of said stop means. 85
24. A computing mechanism including a continuous accumulator and a plurality of totalizers all coaxially mounted, means for driving the continuous accumulator, means for driving each of said totalizers, shifting means for engaging the driving means for said continuous accumulator, individually, and means for engaging any number of totalizers with their driving means. 90
25. In a computing mechanism, a plurality of totalizers each comprising a group of wheels, driving means for each of said totalizers, and stop means shiftable by fractions of the width of a totalizer wheel for selectively positioning one or more totalizers for operation. 100
26. In a combined typewriting and computing machine, a plurality of totalizers, each totalizer comprising a group of wheels, a driving gear for each of said totalizers, stop means shiftable by fractions of the width of a totalizer wheel for selectively positioning one or more totalizers for operation, and means for operating the selected totalizers and coincidentally causing the typewriter to print the number selected. 105
27. A computing mechanism engaged with a typewriter, comprising a casing, totalizers movable therein, means for simultaneously actuating a predetermined group of said totalizers and said typewriter, said means per-
- mitting arrangement of the computed numerals in any position on a typed sheet. 110
